UNITED STATES PATENT OFFICE.

WILLIAM D. SKIDMORE, OF NEW YORK, N. Y.; EMMELINE M. SKIDMORE, ADMINISTRATRIX OF THE ESTATE OF SAID WILLIAM D. SKIDMORE, DECEASED, ASSIGNOR OF ONE-HALF TO FRANCIS DE LANCEY ROBINSON.

DUMPING-CAR.

1,293,954.

Specification of Letters Patent. Patented Feb. 11, 1919.

Application filed June 28, 1916. Serial No. 106,391.

To all whom it may concern:

Be it known that I, WILLIAM D. SKIDMORE, a citizen of the United States, and a resident of the borough of the Bronx, city 5 and State of New York, have invented certain new and useful Improvements in Dumping-Cars, of which the following is a specification.

My invention relates to railroad cars, and 10 more particularly to that class of cars known as dumping cars, such as are used, for instance, in railway construction, for conveying ballast, filling material and the like to such places where it may be needed, and 15 dumping the same upon or beside the right of way; and which may be used for other similar purposes. The invention is also applicable to vehicles of other kinds.

The object of my invention is to provide 20 such a car which shall be simple in construction and efficient in operation, and which is adapted to dump its load on either side or both sides of the right of way, either close to the rails or at a greater distance 25 therefrom, as may be desired, or between the rails, either close thereto or in the middle of the track, and which, on account of its low center of gravity, is capable of being constructed with a large carrying capacity.

30 The invention consists in the novel construction, arrangement and combination of various devices, elements and parts, as shown in the accompanying drawings and fully described in this specification.

35 In the said drawings, Figure 1 is a side elevation of the car; Fig. 2 is an enlarged elevation of one end with the trucks removed; Fig. 3 is a diagrammatic view showing my car arranged to dump on both sides 40 of the right of way, at a distance from the rails; Fig. 4 is a diagrammatic view showing an arrangement whereby the load is dumped at a distance outside the right hand rail only; Fig. 5 is a diagrammatic view 45 showing at the left an arrangement whereby the load is dumped outside the rail and close thereto, and at the right an arrangement by which the load is dumped in the center of the track; Fig. 6 is a diagrammatic view 50 showing an arrangement for dumping the load inside a bin, for instance, inside the rails, but close thereto; Fig. 7 is a detail view of a portion of the dumping mechanism; Fig. 8 is a detail view to be herein-

after described; Fig. 9 is a view on an enlarged scale of the right hand end of Fig. 1; and Fig. 10 is a view on an enlarged scale of the left hand end of Fig. 1.

In carrying my invention into effect in the embodiment thereof which I have selected 60 for illustration in the accompanying drawings and description in this specification, I provide for the lower portion of the car a running gear of the common or any suitable type, comprising the necessary sills, bolsters 65 or the like, mounted upon bogie-trucks provided with journal boxes forming the bearings for the ends of the axles, and supported by and secured to the running gear in any suitable manner are end members 12 connected by means of a portion 13 adapted to form part of the floor of the carrying body of the car.

Extending the length of the car are doors 14, hinged to the members 13 at 15; door 75 16, hinged at 17; doors 18, hinged at 19; and doors 20, hinged at 21. The doors 14, 16 and 18, together with the portions 13, form the bottom of the carrying body, while the doors 20 form the sides.

At one end and on each side of the car I provide levers 22 (see Figs. 7 and 9). These levers 22 are pivoted on the outside of the members 12, and each lever is rigidly secured to a rod 23 running the length of the car. Rigidly mounted on the rods 23 are one or more supports 24, adapted when the lever 22 is in the position shown by the full lines in Fig. 7 to support members 25 rigidly secured to the doors 14, and thus hold the said 90 door in its closed position. When the lever 22 is moved into the position shown by the dotted lines in Fig. 7 the supports 24 are moved out from under the members 25 in order that the door 14 may open. The lever 95 22 may be secured in its full line position by means of a pin 26 passing therethrough, which pin may be secured to the member 12 by a chain 27, in order that it may not be lost. When the lever 22 is in its dotted line position, it rests against a block 28. After the door 14 has been opened, it may be replaced in its closed position by means of a lever 29, which may be detachably secured to a squared end 30, which is a prolongation 100 of the hinge 15. Pawls 32 and ratchets 31 may be provided on the outside of the member 12, at the ends of the said hinges 15.

The doors 16 are supported in a similar manner by means of longitudinal rods 123, supports 124 extending upwardly therefrom adapted to engage with members 125 on the door, and levers 122 rigidly mounted on one end of each of these rods, these levers 122 may be secured by pins 126 which may be attached to chains 127 in order that they may not be lost. Each door 16 is provided with a ratchet 37, engaged by a pawl 38, which pawl is normally held in position by a spring 40, but may be disengaged from the ratchet 37 by operating the handle 39. The door 16 may be replaced in its closed position by applying the lever 29 to the squared end 36, as will be readily understood.

Secured to one end of each hinge 21 is a toothed quadrant 41. (See Figs. 1, 2 and 10). Each quadrant is secured by means of a removable pin 45 to one of the doors 20, in order that it may either be rigid therewith, or swing on 21 as a pivot independently of the said door. A rod 42 is pivoted at 43 to each quadrant, and has its other end pivoted at 44 to one of the doors 18.

I provide levers 46, pivoted at 47, and provided with projections 48 adapted to engage with notches 68 on the quadrants 41. Each of these projections normally engages a notch in a quadrant, and holds the quadrant in whichever position it may occupy, being acted upon by the spring 49, but the projection may be disengaged by depressing a pedal 50, pivoted at 51, and adapted to elevate a vertical rod 52. The upper end of this rod 52 bears against the end of the lever 46 opposite to that which bears the projection 48, raises this end, and so depresses the projection 48.

One pedal 50 is provided on each side of each end of the car, and the pedals on opposite ends of the same sides of the car are operatively connected together so that when one such pedal is depressed, the corresponding pedal at the other end of the car will also be depressed. To accomplish this I provide for each pedal a link 100 having one of its ends pivoted to the inner end of the said pedal. The other ends of the links 100 are pivoted to rocking bars 101, which bars extend inward to the transverse center line of the car, being pivoted midway their length, at 103. To the inner end of each bar 101 is pivoted one end of a link 102. Thus the quadrants 41 may be released from either end of the car.

I also provide securing means 53, pivoted near the top of the ends of the car, at 54, and normally held in the position shown by the full lines in Fig. 2 by means of chains 55. Each member 53 is provided with a pin 56, which, when the member occupies its vertical position, as shown by the dotted lines at the right of Fig. 2, engages with one of

the quadrants 41, and will permit the said quadrant to swing downward for a short distance only, when the projection 48 is released.

I provide a cylinder 57 having suitable stop-cocks 58, for compressed air or the like, and having a piston 59 provided with a rod 60. This rod 60 bears two vertical racks 61, adapted to engage with toothed wheels 62, mounted on shafts 63, which shafts also bear gear wheels 64 adapted to engage with the quadrants 41. The shafts 63 are adapted to slide longitudinally, as shown in Fig. 1, and when in its full line position to place the gears 62 and 64 in engagement with the racks 61 and quadrants 41 respectively, but when in its dotted line position to disengage said gears. Projecting from the members 12 are studs 65, over which may be slipped a gear wheel 66 (see Fig. 8) adapted to rotate thereon, said gear wheel being provided with a handle 67 whereby it and a quadrant 41 engaged thereby may be rotated by hand.

The operation of my invention is as follows:

When it is desired to use the car to dump on both sides of the roadbed, but not close to the rails, as shown in Fig. 3, all the doors are closed, the pins 45 inserted, rigidly attaching the quadrants 41 to the doors 20, and the members 53 placed in their inoperative position, and the car may then be loaded. In order to dump, the gear wheels 62 and 64 are disengaged, and the pedals 50 depressed, releasing the quadrants 41, and the doors 18 and 20. Under the weight of the load, the weight of the quadrants 41, and the momentum acquired from the initial push of the load, these doors open to their full extent, and are held so by the engagement of the projections 48 with the inner notches 68 of the quadrants 41. The momentum of the falling load will throw it away from direct contact with the rails.

When it is desired to close the doors, the pedal 50 is again depressed, and the doors caused to move back into position by hand or by the compressed air.

When it is desired to dump from one side only, as shown in Fig. 4, the pin 45 is withdrawn from each quadrant of the door 20 which is not to be used, this door 20 being then swung inward into the position shown in Fig. 4, where it may be secured in any suitable manner, as by passing pins through its lower flange into the portion 18. The load may then be placed on the car, and will occupy the area shown in cross-section by the shading of Fig. 4. To dump, the mechanism on one side only is employed.

When it is desired to dump outside the track, but close to the rails, as shown at the left of Fig. 5, the members 53 are placed in engagement with the quadrants 41, thus permitting the doors 18 and 20 to open for a

short distance only. The load drops out gradually and without much momentum, and falls close to the rails.

When it is desired to dump in the center of the track, as shown at the right of Fig. 5, the doors 20 are swung inward, and angles or girders 69 suitably secured to their lower edges, as by bolting the flanges of these girders and the doors 20 together. The

10 lengthened door is then allowed to swing outward until it rests against the upper edge of the door 16. The load is dumped through the doors 14, which are opened by disengaging the pawl 32 from the ratchet 31, and operating the lever 22. After the load is dumped, the door may be closed by rotating the handle 29, and the lever 22 then moved back to its full line position, the supports 24 being sprung under the members 25.

20 When it is desired to dump between the rails, but close to them, as shown in Fig. 6, the load is dumped through the doors 16, which are opened by releasing the pawl 38 and disengaging the supports by means of 25 the levers 122 on the side of the car. The operation of these doors is similar to the operation of the doors 14. The doors may be again closed by placing the handle 29 on the squared ends 36, the operation being 30 similar to that of closing the doors 14, except that the handle is moved in the opposite direction.

The advantages of my invention will be obvious from what has been above said concerning its construction and mode of operation, and consists notably of the various manners in which the car may be caused to dump its load and its low center of gravity, which being located approximately at 40 the point 70 of Fig. 3, will permit a large load to be carried. I do not limit myself to the exact form described, as it is obvious that various modifications might be made, without departing from the spirit and scope 45 of my invention.

Having thus described my invention what I claim as new and desire to secure by Letters Patent is as follows:

1. In a dumping car, the combination 50 with running gear and a carrying body; of a side door hinged at its upper extremity, a side door hinged at its lower extremity, a bottom door hinged at its upper extremity, a bottom door hinged at its lower 55 extremity, and means adapted to operate the said doors.

2. In a dumping car, the combination 60 with running gear and a carrying body; of a side door hinged at its upper extremity, a side door hinged at its lower extremity, a bottom door hinged at its upper extremity, a bottom door hinged at its lower 65 extremity, means adapted to operate the said side doors, and means adapted to operate 70 one of the said bottom doors, said last

named means comprising a lever mounted on one end of said car, a rod rigidly secured to said lever and running longitudinally of said car, and a support extending laterally from said rod and adapted to hold 70 said door in a closed position.

3. In a dumping car, the combination 75 with running gear and a carrying body; of a side door hinged at its upper extremity, a side door hinged at its lower extremity, a bottom door hinged at its upper extremity, a bottom door hinged at its lower extremity, means adapted to operate the said side doors, and means adapted to operate 80 one of said bottom doors, said last named means comprising a lever mounted on one end of said car, a rod rigidly secured to said lever and running longitudinally of said car, a support extending laterally from said rod and adapted to hold 85 said door in a closed position, a member located on said door and adapted to rest on the end of said laterally extending support, and a removable pin adapted to normally hold said lever against movement. 90

4. In a dumping car, the combination 95 with running gear and a carrying body; of a side door hinged at its upper extremity, a side door hinged at its lower extremity, a bottom door hinged at its upper extremity, a bottom door hinged at its lower extremity, means adapted to operate the said side doors, means adapted to open one of said bottom doors, and means adapted to close 100 said door, said last named means comprising a ratchet mounted axially of the hinge of said door, a pawl adapted to engage with said ratchet, means adapted to disengage said pawl from said ratchet, a squared end mounted axially of said hinge, and removable means adapted to engage with said squared end. 105

5. In a dumping car, the combination 110 with running gear and a carrying body; of a side door hinged at its upper extremity, a side door hinged at its lower extremity, a bottom door hinged at its upper extremity, a bottom door hinged at its lower extremity, means adapted to operate said bottom doors, and means adapted to operate said side doors, 115 said last named means comprising a quadrant secured to one of said side doors, a rod pivoted to said quadrant and to the other of said side doors, and means adapted to hold or release said quadrant. 120

6. In a dumping car, the combination 125 with running gear and a carrying body; of a side door hinged at its upper extremity, a side door hinged at its lower extremity, a bottom door hinged at its upper extremity, a bottom door hinged at its lower extremity, means adapted to operate said bottom doors, and means adapted to operate said side doors, said last named means comprising a quadrant secured to one of said side doors, a rod 130

pivoted to said quadrant and to the other of said side doors, means adapted to hold or release said quadrant, and means adapted to partially release said quadrant and permit same to move for a short distance only.

7. In a dumping car, the combination with running gear and a carrying body; of a side door hinged at its upper extremity, a side door hinged at its lower extremity, a bottom door hinged at its upper extremity, a bottom door hinged at its lower extremity, means adapted to operate said bottom doors, and means adapted to operate said side doors, said last named means comprising a quadrant secured to one of said side doors, a rod pivoted to said quadrant, and to the other of said side doors, a plurality of sockets in said quadrant, a lever provided with a tooth adapted to normally engage one or the other of said sockets and hold said side doors in either open or closed position, and a tread adapted to move said lever and release said tooth.

8. In a dumping car, the combination with running gear and a carrying body; of a side door hinged at its upper extremity, a side door hinged at its lower extremity, a bottom door hinged at its upper extremity, a bottom door hinged at its lower extremity, means adapted to operate said bottom doors, and means adapted to operate said side doors, said last named means comprising a quadrant secured to one of said side doors, a rod pivoted to said quadrant, and to the other of said side doors, a plurality of sockets in said quadrant, a lever provided with a tooth adapted to normally engage one or the other of said sockets and hold said side doors in either open or closed position, and a tread on each end of the car, said treads being operatively connected together and adapted to move said lever and release said tooth.

9. In a dumping car, the combination with running gear and a carrying body; of a side door hinged at its upper extremity, a side door hinged at its lower extremity, a bottom door hinged at its upper extremity, a bottom door hinged at its lower extremity, means adapted to operate said bottom doors, and means adapted to operate said side doors, said last named means comprising a quadrant secured to one of said side doors, a rod pivoted to said quadrant and to the other of said side doors, means adapted to hold or release said quadrant, and means adapted to move said quadrant.

10. In a dumping car, the combination with running gear and a carrying body; of

a side door hinged at its upper extremity, a side door hinged at its lower extremity, a bottom door hinged at its upper extremity, a bottom door hinged at its lower extremity, means adapted to operate said bottom doors, and means adapted to operate said side doors, said last named means comprising a quadrant secured to one of said side doors, a rod pivoted to said quadrant and to the other of said side doors, means adapted to hold or release said quadrant, and means adapted to move said quadrant; said last named means comprising gear teeth on said quadrant, a gear wheel adapted to be removably applied to said teeth, and means adapted to rotate said gear wheel.

11. In a dumping car, the combination with running gear and a carrying body; of a side door hinged at its upper extremity, a side door hinged at its lower extremity, a bottom door hinged at its upper extremity, a bottom door hinged at its lower extremity, means adapted to operate said bottom doors, and means adapted to operate said side doors, said last named means comprising a quadrant secured to one of said side doors, a rod pivoted to said quadrant and to the other of said side doors, means adapted to hold or release said quadrant, and means adapted to move said quadrant; said last named means comprising gear teeth on said quadrant, a cylinder on said running gear, a piston adapted to work in said cylinder, a rack operated by said piston, and means adapted when in one position to operatively connect said rack and quadrant together and when in another position to leave them free of each other.

12. In a dumping car, the combination with running gear and a carrying body; of a side door hinged at its upper extremity, a side door hinged at its lower extremity, a bottom door hinged at its upper extremity, a bottom door hinged at its lower extremity, means adapted to operate the said doors, and means whereby said first named door may be swung inward, and secured against opening.

13. In a dumping car, the combination with running gear and a carrying body mounted thereon; of a door swingingly mounted in said carrying body, a side member swingingly mounted in said carrying body, and a member detachably securable to said side member, whereby its vertical length is adapted to be increased.

In witness whereof I have hereunto signed my name this 26th day of June, 1916.

WILLIAM D. SKIDMORE.
